APPARATUS FOR PERFORATING SHEET MATERIAL

John W. Meaker, New York, N. Y.

Application October 26, 1945, Serial No. 624,809

5 Claims. (Cl. 219—29)

1

This invention relates to mechanism for the electro-perforation of sheet material. It is an object of the invention to produce a device of this character which will perforate rapidly moving sheet material over an extensive area.

The principles of the invention will be defined in the claims ultimately appended hereto. It will be illustrated by the following description taken in conjunction with the drawings, in which

Fig. 1 is an end view of rows of electrodes.

Fig. 2 is a side view of the device partly in section.

Fig. 3 is a detailed view of an electrode support shown partly in section.

Fig. 4 is a plan view of part of a lower electrode bar with the electrodes shown thereon.

Looking at the drawings 1 designates a piece of sheet material such as paper or the like and 2a, 2b, 3a, and 3b show feed rolls designed to move the sheet material through the machine. At 5 is a support or platform preferably made of glass or some insulating wear resistant plastic. In the supporting platform 5 are slots 6, 7, 8 and 9, through the platform and disposed at right angles to the path of travel of the sheet material. In these slots are arranged the lower electrode supporting bars 10, 11, 12 and 13. These bars are arranged so that the tops thereof are in the slots 6, 7, 8 and 9 respectively. The tops of these bars are curved as shown in Fig. 2 and each bar is designed to support thereon a number of spring clip type electrodes such as those shown at 15, 16, 17 and 18 of Fig. 2. Fig. 1 shows any one of the rows of electrodes but we will call it the first row at the right end as viewed in Fig. 2 so that the lower bar is bar 10 and the upper bar 20. The various spring clip electrodes on bar 10 are designated 15a, 15b, 15c, 15d and 15e (see Fig. 1). Fig. 4 illustrates the supporting bar 10 and the electrodes 15a, 15b, 15c and 15d. These spring clip electrodes are made out of spring wire bent into the shape shown in the figures so that they will embrace the top and sides of the various supporting bars 10, 11, 12 and 13. There is sufficient friction between the bars and the spring electrodes so that the latter will not move accidentally yet can be positioned merely by sliding them along the bar. It is obvious that they are readily removed and replaced when this becomes necessary.

The upper swingable electrodes are mounted on supporting bars 20, 21, 22 and 23. These bars are made of insulating material such as "Mycalex," "Ebonite" or other plastic. Each bar is equipped with two or more lugs or ears, one

2

of which is shown on bar 20 at 25. Similar lugs or ears on bars 21, 22 and 23 are shown at 26, 27 and 28, respectively. These lugs are designed to be attached by a suitable screw or bolt shown at 30, 31, 32 and 33 to supporting members 35, 36, 37 and 38 attached to the framework of the machine. This kind of support permits the bars to be rotated about the screws or bolts 30, 31, 32 and 33 for adjustment if that becomes necessary.

On the opposite side of each bar are electrode supporting lugs. Some of these are shown at 40, 41, 42 and 43 in Fig. 2. These lugs may be integral with the bars 20, 21, 22 and 23 or attached thereto by suitable screws shown at 45 and 46 on bar 22. The screws for holding all the other lugs on the various bars 20, 21, 22 and 23 are the same and will not be given additional reference characters.

In Fig. 1 the lugs on bar 20 have been designated 40, 40a, 40b and 40c. Each lug supports two pivoted electrodes such as those shown at 50a, 51a, 52a and 53a. Electrodes on bar 20 are designated at 50a, 50b, 50c, 50d, 50e, 50f and 50g, as shown in Fig. 1. Each electrode is made of suitable conducting material, preferably metal, which will readily conduct electricity and at the same time resist wear as the sheet material passes under the end thereof. Electrodes must have sufficient weight or be equipped with a spring so that they will stay down to contact with the sheet material even when the latter is travelling at relatively high speed.

Through each of the lugs such as those shown at 40, 41, 42 and 43 are supporting pins. Each lug has the same kind of a pin and only one will be described. Looking at Fig. 3, the pin is shown at 50, it passes through the lug 42 parallel to the longitudinal axis of the bar 22. The pin 50 projects on both sides beyond the lug 42 and on the projecting ends thereof the movable electrodes are hung. In order to attach the electrodes, circular grooves, such as those shown at 51 and 51', are cut near the ends of the pin 50.

The electrodes are secured on the pin 50 by means of screws such as those shown in Fig. 3 at 55 and 56. These screws are threaded into tapped holes in the electrodes and have projecting ends or dogs which engage in the grooves 51 and 51' so that the electrodes 52a and 52b are free to pivot around the pin 50 but may not move axially thereof.

Each pair of upper and lower supporting bars such as bars 10 and 20 are positioned relative to

each other so that the lower ends of the upper electrodes on the upper bar are arranged when in lowermost position just above the center of the top edge of the lower bar. For instance, looking at Fig. 2 we see that the lowermost portion of the electrode 50a is positioned just above the top edge of the bar 10. Supporting bars 11 and 21 and 12 and 22 and 13 and 23 are arranged in the same relative position to each other.

The spring clip electrodes disposed on the lower supporting bars are arranged so that one arm thereof is underneath one of the upper electrodes while the other arm of the same clip is under the adjacent upper electrode of another pair. This is clearly shown in Fig. 1. For example, looking at spring clip 15b we see that arm 60 is underneath upper electrode 59b whereas arm 61 is underneath upper electrode 50c. The upper edges of the spring clip electrodes where the wire is bent over the upper edge of the supporting bars therefor are arranged so that they are on substantially the same level as the upper surface of the platform 5 so that the bottom of the sheet material passing along the platform 5 will just make contact with the wire clip lower electrodes. The weight of the upper electrodes pressing downwardly on the sheet material will press the sheet material between upper and lower electrodes as it moves along over the platform 5.

Each spring clip lower electrode bridges over the space between a pair of adjacent upper electrodes. The adjacent electrodes are not however mounted on the same pin. Current for perforating the sheet material may be supplied to either the upper or lower electrodes and at 63 and 64 are shown connections for applying current to the lower electrodes. Each row of electrodes is supplied with current as shown in Fig. 1. The current coming in through wire 64, for instance, passes up through the spring clip 15a through the sheet material 1 to electrode 50a, it would then pass through the support pin for this electrode such as pin 50 and down through the adjacent electrode 50b to spring clip electrode 15b. In this way the current would pass up and down through the sheet material and along the rows of electrodes. Each time that it passed from an upper to a lower electrode and through the sheet material it would perforate the latter.

The various rows of electrodes as shown in Fig. 2 may be staggered in relation to each other so that the net result of a series of rows is to perforate an area of the sheet material as it passes through the machine.

At 70, 71, 72 and 73 of Fig. 2 are shown pins for limiting the downward movement of the electrodes 50a, 51a, 52a, and 53a. Each of the upper electrodes is equipped with such a pin so that its downward motion can be so limited.

The present invention is not limited to any particular electric circuit or electric means for supplying the necessary sparks to perforate the sheet material but an apparatus such as that described in Meaker Patent #2,372,508 may be used to supply the current to the electrodes described in this application.

In the light of the foregoing description the following is claimed.

1. In a device of the character described an upper and lower row of electrodes, supporting means therefor, said lower electrodes comprising a series of wire clips disposed over the edge of the support therefor, each clip having two arms bent over the upper edge of the support and each clip designed to embrace the support with suf-

ficient spring tension and friction to maintain its position thereon, said upper electrodes consisting of pivoted arms mounted in pairs, the arms of each pair being electrically connected and each arm designed to cooperate with one arm of a pair of different spring clip electrodes on the lower bar to perform the perforating operation on the sheet material passing between the electrodes.

10 2. In a device of the character described, rows of upper and lower electrodes, rigid supporting bars for said electrodes, said lower electrodes comprising bent wire shaped in the form of a double U and designed to engage the edge of the

15 support on which it is positioned by means of spring tension sufficient to prevent accidental displacement yet designed to permit the electrode to be slid along the supporting means to any desired position, and swingable upper electrodes adapted to cooperate with said lower electrodes to perforate sheet material passing therebetween.

3. In a device of the character described a supporting platform over which sheet material

25 may be passed, slots arranged in said platform at right angles to the direction of travel of said sheet material, insulating rigid supporting bars disposed beneath said slots, each bar equipped with a plurality of spring clip electrodes each of 30 which has a pair of arms disposed over the upper edges of said bar, supporting bars over said platform and pivoted electrodes thereon designed to cooperate with the spring clip electrodes to transmit electric current from the upper 35 to the lower electrodes for the purpose of perforating sheet material passing along the platform.

4. In a device for electrically perforating dielectric sheet material having two rows of co-

40 operating electrodes facing each other and arranged to receive between them the material to be perforated, the combination including a support of insulating material, a series of spring clips bent into the form of a double U with two pairs of oppositely disposed arms, one pair of which are connected together at their free ends; said U-shaped arms slidably gripping said support on opposite sides thereof with sufficient friction and tension to maintain said clip in position 45 on said support and each of said spring clips including two electrode portions disposed at one edge of the support in opposed relation to cooperating electrodes in the other row of electrodes, the electrode portions of each of said clips being connected electrically through other portions of their respective clips.

5. In a device for electrically perforating sheet

50 material having two rows of cooperating electrodes facing each other and arranged to receive between them the material to be perforated, the combination including a rigid supporting bar of insulating material and a series of double spring-clips each forming twin electrodes carried by said supporting bar, each electrode facing an electrode in the other row of electrodes and comprising a U-shaped portion frictionally embracing the sides of the supporting bar and with the bight of the U engaging the edge of the supporting bar, the two U-shaped portions being mechanically and electrically connected by an integral portion joining one leg of one U-shaped portion to one leg of the other U-shaped portion.
